(57) **CLAIM**

The ornamental design for a fluid guiding device for electrolyzer, as shown and described.

DESCRIPTION

FIG. 1 is a perspective view of a fluid guiding device for electrolyzer;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is enlarging a portion of the front view of FIG. 2 of the fluid guiding device for electrolyzer.

The dashed broken lines in the drawings illustrate example environment that form no part of the claimed design.

1 Claim, 7 Drawing Sheets
